Primary Examiner—Susan J. Lucas*Assistant Examiner*—Cynthia E. Ramirez*Attorney, Agent, or Firm*—Michael J. Kline; Paul D. Bangor; Charles E. Kosinski**[57] CLAIM**

The ornamental design for the dry iron, as shown and described.

DESCRIPTION

FIG. 1 is a front perspective view of the dry iron of the present invention;

FIG. 2 is a left side elevational view of the dry iron of FIG. 1, which also illustrates the identical right side elevational view of the dry iron of FIG. 1;

FIG. 3 is a rear elevational view of the dry iron of FIG. 1;

FIG. 4 is a top plan view of the dry iron of FIG. 1;

FIG. 5 is a bottom plan view of the dry iron of FIG. 1; and,

FIG. 6 is a front elevational view of the dry iron of FIG. 1.
